Filed Oct. 1, 1968, Ser. No. 13,798

Term of patent 14 years

Int. Cl. D26—02

U.S. Cl. D48—20

FIG. 1 is a perspective view of the beam lamp or the like embodying my new design, the counterbalance supporting arm assembly being shown in broken lines for illustrative purposes only.

FIGS. 2 and 3 are side elevational views, the tubular rod being omitted in FIG. 3 for convenience of illustration.

FIGS. 4 and 5 are top and bottom views, respectively.

The design is characterized by the features of the opaque lamp housing.

The four side elevations are identical except for the rectangular projection shown at the right-hand edge of FIG. 2 and in the upper central portion of FIG. 3.

I claim:

The ornamental design for a beam lamp or the like, as shown and described.
